UNITED STATES PATENT OFFICE.

CHARLES T. McELYANEY AND WILLIAM H. WILSON, OF PARSONS, KANSAS.

FUEL MIXER AND EJECTOR.

Application filed August 18, 1921. Serial No. 493,376.

To all whom it may concern:

Be it known that we, CHARLES T. McELYANEY and WILLIAM H. WILSON, citizens of the United States, residing at Parsons, in 5 the county of Labette and State of Kansas, have invented certain new and useful Improvements in Fuel Mixers and Ejectors, of which the following is a specification.

This invention relates to a fuel ejector 10 and mixer for burners and the like; for use in connection with steam generators, boilers, and other like structures, and the primary object of the invention is to provide a novel and simple device embodying a fuel bowl 15 having an air inlet, and an ejector for sucking in fuel and air and for mixing the same and forcing the mixed product in the nature of an inflammable vapor or gas, to the point where the same is to be used.

Another object of the invention is the provision of a novel fuel ejector and mixer, which is of exceptionally simple and durable construction, and which embodies a minimum number of parts, and which will direct a constant stream of mixed fuel and air in varying quantities according to the pressure of the steam or air flowing through the ejector, and which embodies automatic means for controlling the flow of fuel into 30 the body of the device.

Another object of the invention is to provide an improved means for feeding fuel to the burners of steam boilers and the like, which eliminates the necessity of applying 35 pressure to fuel storage tanks, thereby adding to the life of said tank and preventing the ready forming of leaks therein, and which permits burning of all kinds of liquid fuel, and embodies means for thoroughly 40 mixing the fuel with air to form an inflammable mixture, thereby decreasing the fuel consumption and permitting a hotter fire to be had at the burner.

With these and other objects in view, the 45 invention consists in the novel construction, arrangement and formation of parts, as will be hereinafter more specifically described, claimed and illustrated in the accompanying drawings, forming a part of this specification, in which drawings:

Figure 1 is a longitudinal section through the improved fuel mixer and ejector taken on the line 1—1 of Figure 2, and

Figure 2 is a vertical transverse section

through the improved device, taken on the 55 line 2—2 of Figure 1.

Referring to the drawings in detail, wherein similar reference characters designate corresponding parts throughout the several views, the letter A indicates the improved mixer and ejector, which includes the liquid fuel bowl 5. This bowl 5 may be of any desired shape or form and constructed of any desired material. As shown in the drawings, the bowl 5 is substantially semi-spherical shaped, and can be made in one or more parts. An upper section 6 is provided for the bowl and includes a flat plate 8 which overlies the upper surface of the bowl and is connected thereto, by means of 65 suitable cap screws 9'. The bowl 5 at one end thereof has communicating therewith a fuel inlet pipe 9, which leads into a laterally extending chamber 10. This chamber 10 has secured thereto in any preferred manner, as at 11, the fuel supply pipe 12. A valve seat 13 is formed in the chamber 10 and is adapted to receive the valve 14, which is utilized for controlling the flow of fuel from the supply pipe 12 into the chamber 10 70 and into the bowl 5. The valve 14 is controlled by a float 15, which is mounted within the bowl 5, and it can be seen that the float 15 is adapted to raise or lower with the fuel in the bowl. This float 15 can be 75 made in any desired manner and of any preferred material. That is, the same can be made of wood or cork, or of hollow construction and out of metal. The float 15 has secured thereto the rearwardly extending arm 80 16, which is fulcrumed, as at 17, on a pivot pin which is carried by the sides of the fuel inlet pipe 9. By this construction, upon the raising or lowering of the float 15, the valve 14 will be raised or lowered therewith. 85 A suitable removable cap 18 can be provided, for the chamber 10, in order to permit ready access to be had to the valve 14 and the seat 13, in order to permit repairs or replacement thereto.

Extending radially into the chamber 5 and terminating adjacent to the axial center thereof is an air inlet tube 20. This tube 20 is provided with an inwardly and upwardly extending offset end 21, which is 90 adapted to communicate with a central opening 22 formed in the upper section 6. This opening 22 receives a hollow cylindrical pipe

23 which seats in the offset end 21. The air inlet pipe 20 also has communicating therewith a depending inclined projection 24, which supports the inwardly extending 5 valve housing 25. The inner end of this valve housing 25 terminates at the axial center of the tube 23 and receives an ordinary type of needle valve 26. This needle valve 26 projects outwardly from the lower 10 end of the bowl and is provided with a handle 27. A suitable packing gland 28 can be provided for the needle valve 26, in order to prevent the leakage of the liquid around the same. The valve opening in the 15 casing 25 can be formed relatively large if so desired, owing to the nature of the fuel used with the combined ejector and mixer.

If found desirable, the float 15 can be slotted, as at 29, in order to receive the air feed 20 pipe 20.

If found desirable, the lower end of the bowl may be provided with a pet cock 30, in order to permit the draining of any sediment from the lower part of the bowl.

25 The upper section 8 supports the ejector 35, which forms an important part of the invention. The ejector 35 includes a body 36, which is formed integral with the stop plate 8, and extends at right angles to the 30 tube 22, which projects into the same. The body 36 is provided with a reduced internally threaded bore 37, which receives an ejector nozzle 38. This nozzle 38 extends into the body 36 and into a second nozzle 39, which is formed relatively larger in diameter than the nozzle 38. As shown the inner end of the nozzle 39 is flared as at 40, in order to facilitate the receiving of the inner end of the nozzle 38. The nozzle 40 39 is provided with a screw threaded portion which is fitted in a screw threaded bore 41 formed in the body 36. One end of the body 36 receives a suitable supply pipe 42, which is connected thereto in any preferred manner as at 43. The pipe 42 supplies the air or steam under pressure to the nozzle 38, and the fluid forcibly flowing through the nozzle will suck the fuel from the bowl 5 and air from the air tube 20 into the body or 45 chamber 36 where the same will be intermixed and sucked into the nozzle 39 by the steam or air pressure and then ejected out of the nozzle into a lead pipe 45, which can extend to a suitable burner or the like. The 50 lead pipe 45 can be connected to the body 36 in any preferred manner.

The use of the invention is unlimited, and can be effectively used in connection with the steam engine of motor vehicles owing to the 55 compact and efficient nature thereof, and the fact that the fuel can be automatically controlled by the amount of steam or air admitted into the pipe 42.

Changes in details may be made without departing from the spirit or scope of this 65 invention, but;

We claim:

1. A fuel mixer and ejector comprising a fuel bowl, a fuel inlet pipe communicating with the bowl, an air inlet pipe extending into the bowl, means for automatically regulating the amount of fuel in said bowl, means connecting the air pipe with the bowl, a valve for controlling the flow of fuel into the inlet pipe, a body carried by the bowl, an ejector nozzle in said body, and means connecting the body with the air inlet pipe. 70

2. A combined mixer and ejector comprising a fuel bowl, a fuel pipe communicating with the bowl, means for automatically governing the flow of fuel into the bowl through said pipe, an air inlet pipe extending into the bowl, a chamber carried by the upper end of the bowl, means for establishing communication between the air inlet pipe and chamber, an ejector nozzle disposed in the chamber, a second nozzle communicating with the chamber and receiving the free end of the first ejector nozzle, means for establishing communication between the fuel chamber and the air inlet pipe, a manually operable valve disposed in the fuel pipe for controlling the flow of fuel into said air inlet pipe. 85

90 3. A combined mixer and fuel ejector comprising a bowl for receiving fuel, a fuel pipe communicating with the bowl, an air inlet pipe extending into the bowl, a chamber carried by the upper end of the bowl, a laterally extending offset terminal formed on the inner end of the air inlet pipe, a pipe communicating with the air inlet pipe and with the chamber, a laterally extending nipple formed on the air inlet pipe and 100 communicating with the fuel bowl, a valve seat formed in said nipple, a valve for controlling the flow of fuel past said seat, a pressure pipe communicating with one end of the chamber, an ejector nozzle arranged 110 in the chamber and communicating with said pressure pipe, and an outlet nozzle communicating with the chamber and arranged to receive the free end of said first mentioned nozzle. 115

4. In a fuel ejector and mixer for burners, a fuel bowl, a fuel inlet pipe extending into the bowl, an air pipe extending into the bowl, an outlet fuel and air pipe, a feed pipe communicating with the outlet pipe, and an 120 ejector nozzle extending into the feed pipe and disposed directly above the outlet fuel and air pipe.

CHARLES T. McELVANEY.
